PLANK FENCE

Angus Snead Macdonald, near Rapidan, Va., by Amy B. Macdonald, Frances Macdonald, and Angus Avery Macdonald, executors of said Angus S. Macdonald, deceased, assignors to Everdure, Inc., near Orange, Va., a corporation of Virginia

Filed May 27, 1960, Ser. No. 60,749

Term of patent 14 years

(Cl. D28—1)

FIG. 1 is a side elevation, showing the new design of a plank fence, the portion thereof within dot-and-dash lines representing the pattern of the fence;

FIG. 2 is a top plan view thereof;

FIG. 3 is a side elevation, taken from the side opposite from FIG. 1; and

FIG. 4 is an end elevation thereof.

I claim:

The ornamental design for a plank fence, as shown and described.
